UNITED STATES PATENT OFFICE

2,020,391

RAILWAY CAR

William E. Wine, Toledo, Ohio

Application April 29, 1931, Serial No. 533,848

118 Claims. (Cl. 105—247)

My invention relates to railway cars and more particularly to cars of the hopper type. It has for its principal object the production of an improved center sill which may be conveniently provided with simple means whereby adjoining parts of the car may be associated and connected therewith.

A principal feature of the invention consists in providing the railway car with a cast metal center sill having side walls and an arched top wall.

Another feature of the invention consists in providing the top wall of the center sill which integrally connects the side walls thereof with downwardly diverging portions inclined transversely of the car.

Another feature of the invention consists in providing the cast metal center sill with integrally connected side, top and bottom walls, the side and top walls extending from one end of the sill to the other and the bottom wall terminating inwardly of the ends.

A still further feature of the invention consists in providing the center sill with angularly shaped members for integrally connecting the side walls thereof, the members being preferably disposed adjacent stops or abutments with which the sill may be provided for cooperating with followers of the draft gears of the car.

A further feature of the invention consists in integrally forming the center sill with a center plate which is provided with a hollow substantially cylindrical portion for receiving a center pin, the cylindrical portion being integrally connected to the side walls of the sill by a substantially horizontal web portion.

A still further feature of the invention consists in integrally forming the center sill with a center plate provided with an upwardly extending portion for receiving a center pin, the center pin receiving portion being rigidified by a plurality of substantially vertical ribs, some of which are formed integral with the side walls of the sill.

A still further feature of the invention consists in integrally forming the center sill which is provided with side, top and bottom walls with laterally projecting brackets affording means to which a body bolster may be attached.

A still further feature of the invention consists in integrally providing the spaced walls of the center sill with laterally projecting brackets, each of which has a substantially horizontal plate portion affording means to which a body bolster may be secured, the walls of the sill being integrally connected by a web portion disposed in the plane

of and constituting a continuation of the plate portions of the brackets.

Still another feature of the invention consists in integrally providing the center sill with an upstanding projection affording means to which a body bolster may be secured.

Still another feature of the invention consists in forming the side walls of the center sill with laterally projecting downwardly inclined portions for supportingly cooperating with inclined floor sheets of the car.

Still another feature of the invention consists in providing the center sill with an arched top wall integrally connecting the side walls thereof, flange means being formed integral with the sill and having portions extending across said top wall and downwardly along said side wall affording means to which inclined floor sheets of the car may be secured.

Still another feature of the invention consists in integrally forming the side walls of the center sill with portions adapted to support adjacent portions of the cross ridge sheets of the car.

Still another feature of the invention consists in integrally forming the side walls of the car with laterally projecting members each of which has downwardly diverging portions adapted to underlie and support adjacent portions of a cross ridge sheet of the car.

A still further feature of the invention consists in providing the center sill with a top wall having portions inclined transversely of the car and with laterally projecting members having portions inclined longitudinally of the car.

A still further feature of the invention consists in rigidly providing the center sill with means adapted to be disposed in interlocking relation with portions of a cross bearer.

A still further feature of the invention consists in integrally providing the center sill with upwardly extending members having offset portions adapted to overlie adjacent portions of a cross bearer of the car.

A still further feature of the invention consists in providing, in combination, a center sill, a pair of downwardly diverging inclined floor sheets disposed on each side of the center sill and members respectively rigid with and projecting laterally from the side of the sill, each of said members having diverging portions for supportingly cooperating with adjacent portions of the floor sheets.

A still further feature of the invention consists in providing, in combination, a center sill, brackets mounted on the sides of the car, transversely extending members disposed on opposite

sides of the center sill and respectively secured to said brackets and to the sill, and inclined floor sheets diverging downwardly on opposite sides of said transversely extending members rigidly secured thereto in overlapping relation.

Other and more specific features of the invention residing in advantageous forms, combinations and relations of parts will hereinafter appear and be pointed out in the claims.

10 In the drawings illustrating a preferred embodiment of the invention:

Figure 1 is a plan view of a railway hopper car.

Figure 2 is a side elevational view of the car.

15 Figure 3 is a fragmentary end elevational view of the car.

Figures 4 and 5 are sectional views taken on lines 4—4 and 5—5, respectively, of Figure 3.

Figure 6 is a plan view of somewhat more than one half of the center sill.

20 Figure 7 is a side elevational view of the portion of the center sill shown in Figure 6.

Figure 8 is an enlarged plan view of the portion of the center sill adjacent an end thereof.

25 Figures 9 and 10 are respectively side and bottom elevational views of the portion of the sill shown in Figure 8.

Figure 11 is an end elevational view of the sill.

Figures 12 and 13 are transverse vertical sectional views taken on lines 12—12 and 13—13, respectively, of Figure 8.

30 Figure 14 is a transverse vertical sectional view taken on line 14—14, of Figure 9.

Figures 15 and 16 are longitudinal, vertical sectional views taken on lines 15—15 and 16—16, respectively, of Figure 8.

35 Figure 17 is a fragmentary plan view of the center sill from a point inwardly of the point to which one of the body bolsters is adapted to be secured to a point beyond the center of the sill.

40 Figure 18 is a side elevational view of the portion of the sill illustrated in Figure 17.

Figures 19, 20 and 21 are transverse vertical sectional views taken on lines 19—19, 20—20 and 21—21, respectively of Figure 18.

45 Figures 22 and 23 are longitudinal vertical sectional views taken on lines 22—22 and 23—23, respectively, of Figure 17.

Figure 24 is a fragmentary transverse vertical sectional view taken on line 24—24, Figure 2.

50 Figures 25, 26 and 27 are longitudinal sectional views taken on lines 25—25, 26—26 and 27—27, respectively, of Figure 24.

Figure 28 is a horizontal sectional view taken on line 28—28, of Figure 24.

55 Figure 29 is a longitudinal vertical sectional view of the car adjacent one of the body bolsters showing the manner in which the floor sheets of the car are secured to the center sill.

Figure 30 is a plan view of the portion of the 60 construction illustrated in Figure 29.

Figure 31 is a plan view of one of the sections of the body bolster.

Figures 32 and 33 are respectively side and bottom elevational views of the section of the 65 body bolster shown in Figure 31.

Figure 34 is an end elevational view of the body bolster section as viewed from the right-hand side of Figure 32.

70 Figure 35 is an end elevational view of the body bolster section as viewed from the left-hand side of Figure 32.

Figures 36 and 37 are detail sectional views taken on lines 36—36 and 37—37, respectively, of Figure 32.

75 Figure 38 is a transverse vertical sectional

view of the car taken on line 38—38, of Figure 2.

Figures 39, 40 and 41 are respectively longitudinal sectional views taken on lines 39—39, 40—40 and 41—41, respectively, of Figure 38.

Figure 42 is an enlarged side elevational view 5 of somewhat more than one-half of the cross bearer.

Figure 43 is a top plan view of the portion of the cross bearer illustrated in Figure 42.

Figure 44 is an end elevational view of the 10 cross bearer as viewed from the right-hand side of Figure 42.

Figures 45, 46, 47, 48, 49 and 50 are enlarged detail sectional views taken on lines 45—45, 46—46, 47—47, 48—48, 49—49 and 50—50, respectively, of Figure 42.

Figure 51 is a fragmentary transverse vertical sectional view on line 51—51, of Figure 2.

Figures 52 and 53 are longitudinal vertical sectional views taken on lines 52—52 and 53—53, 20 respectively, of Figure 51.

Figures 54 and 55 are detail sectional views taken on lines 54—54 and 55—55, respectively, of Figure 52.

Referring more particularly to the drawings, 25 for convenience of reference, the center sill is designated by the letter A, the side sills by B, the end sills by C, the body bolster by D and the cross bearer by E. As is well known these parts of the car generally constitute what is 30 termed the underframe.

The sides and ends of the car are respectively formed by metal sheets 1 and 2, respectively. At their lower edges the side sheets are secured to the side sills which, intermediate the body bolsters, are preferably of substantially Z-shape having upper and lower flanges 3 and 4, respectively, connected by a web 5 and, which immediately adjacent the body bolsters and between the latter and the ends of the car are preferably of angle 35 shape having an upwardly projecting vertical flange 6 and an inwardly projecting horizontal flange 7. The flanges 3 and 6 are disposed substantially in vertical planes constituting continuations of each other and it is to these flanges 45 that the lower edges of the side sheets are secured. As is usual the sides of the car are preferably strengthened by side stakes, each of which may advantageously be of angle shape having a flange 8 secured to the sheets and a flange 9 projecting inwardly from the latter. The sides of the car are also preferably formed with top rails 10 to which the upper portions of the side sheets are directly secured and to which the upper portions of the side stakes are indirectly secured by 55 brackets 11.

The end sheets 2 of the car are connected at their side edges to corner posts 12 to which the side sheets adjoining the ends of the car are also secured, each of the corner posts being preferably 60 of angle shape. Along their upper edges the end sheets are secured to top rails 13 of a shape similar to the side top rails 10 while at their lower edges they are provided with inwardly projecting flanges 14 for attachment to adjacent inclined floor sheets 15 of the car. Each end of the car may be advantageously braced or strengthened by a pair of angle members having flanges 16 and 17, respectively. The flanges 16 of these members are rigidly secured at their upper portions to the end top rails 13 and at their lower portions to the upwardly projecting substantially vertical flange 18 of the adjoining end sill.

The center sill A of the car which extends from 75

one end thereof to the other is preferably formed as a single unitary casting having spaced side walls 19 integrally connected by top and bottom walls 20 and 21, respectively. The side walls 5 are substantially vertical and as shown in several of the transverse vertical sectional views are preferably of greater width adjacent their lower portions than adjacent their upper portions while the top wall 20 is preferably arched and has 10 downwardly diverging portions 22 which are inclined transversely of the car. Although the side and top walls extend substantially continuously from one end of the sill to the other the bottom wall terminates inwardly of the ends thereof at 15 substantially the points of the sill to which the body bolsters are secured. To reduce the weight of the center sill and yet not to impair its strength the bottom wall may be provided with a plurality of openings 23, the portions of the 20 bottom wall bounding the openings being preferably formed with upwardly projecting rigidifying ribs 23'.

Adjacent each end of the sill the top wall is provided with a substantially horizontal portion 25 24 to afford a convenient portion to which the inwardly projecting horizontal flange 25 of the adjacent end sill may be rigidly secured. These horizontal portions of the center sill merge into and are integrally connected to the diverging portions 30 22 of the top wall by portions 26 which are inclined longitudinally of the car and progressively decrease in width to adjacent the apex of the top wall. Outwardly of the horizontal portions 24 the center sill is integrally provided with 35 upwardly projecting members 27, each of which is formed with a vertical transversely extending flange 28 and longitudinally extending end flanges 29. The flange 28 serves as a convenient means to which the upwardly projecting flange 18 40 of the adjacent end sill may be rigidly secured while the flanges 29 serve as convenient means to which the outwardly projecting flanges 17 of the angle-shaped and reinforcing members may be rigidly attached. To more securely connect 45 the lower portions of these angle members a plate 30 may be interposed between the vertical flange of the end sill and the member 27, being rigidly connected to each and to the flanges 16 of the angle members.

50 Each end of the center sill may advantageously be integrally provided with a striking casting having a substantially vertical face 31 constituting an end wall portion of the sill and an in-turned substantially horizontal flange 32 formed 55 integrally with the upper portions of the side walls of the sill. The striking casting may, if desired, be reinforced by a plurality of ribs 33 which integrally connect the vertical and horizontal portions 31 and 32 with adjacent portions of the 60 top wall of the sill. The sill may also be provided with carrier irons which in addition to their usual function serve to integrally connect the lower end portions of the side walls of the sill. Each carrier iron may be formed with a substantially horizontal web portion 34 and downwardly 65 projecting marginal flanges 35. If desired, a removable wear member 36 may be interposed between the web 34 of the carrier iron and the shank of an associated coupler illustrated in Figures 3 and 5. Each end of each side wall of the 70 sill may be integrally formed with a substantially vertical flange 37 having portions projecting from opposite sides thereof and disposed in substantially the planes of the face 31 of the adjacent striking casting and the outer one of the flanges 75

35 of the adjacent carrier iron. It will thus be seen that the flanges 37 of the side walls, the face 31 of the striking casting, the outer one of the vertical flanges of the carrier iron form in effect an end wall for the center sill which has an opening for receiving a car coupler.

From adjacent the points to which the body bolsters are adapted to be attached outwardly to its ends the center sill is open on its underside and the side and top walls of these portions of 10 the sill constitute pockets for receiving draft gears. In order to compensate for the omission of the bottom wall at these portions of the sill the lower edges of the side walls are provided with outwardly projecting flanges 38. The pocket portions of the sill are each provided with two pairs of substantially vertical inwardly projecting members 39 formed integrally with the side and top walls for cooperating with draft gear followers (not shown). Each of these members 20 is provided with a plurality of substantially horizontal longitudinally extending reinforcing ribs 40 formed integrally therewith and the adjacent side wall. The inner edges of the adjacent reinforcing ribs are integrally connected by substantially vertical web portions 41 which are disposed in planes inclined with respect to the side walls of the sill. It will thus be observed that the stop members 39 are reinforced by a plurality of substantially channel-shaped members. 30 The side walls of the sill adjacent the forward pair of stop members 39 are provided with aligned openings 42 for receiving a draft gear key 43. The portions of the walls bounding the openings are preferably provided with outwardly projecting strengthening ribs 44, the forward portions of which are connected to portions of the end flanges 37 by additional ribs 45. The laterally projecting flanges 38 of the side walls of the sill are preferably apertured as at 46 to receive rivets 40 or the like for connecting thereto a suitable member (not shown) for supporting the draft gear within the pocket. To relieve these flanges from strain at the points to which the draft gear supporting members are adapted to be attached they 45 are preferably provided with strengthening ribs 47 formed integral with the side wall.

Inwardly of the rear pair of follower stops 39 the side walls are preferably integrally connected substantially midway between their upper and 50 lower edges by an angularly shaped member which may be advantageously of channel shape having a substantially horizontal web 48 and downwardly depending substantially vertical marginal flanges 49. Thus it will be perceived 55 that the side walls of the sill are adequately tied together to prevent them from spreading, due to shocks imparted thereto from the draft gears.

Adjacent its end portions the bottom wall of the center sill is integrally formed with depressed 60 circular portions 50 respectively constituting center plates of the center bearings of the car. At their central portions each of the center plates is formed with an upwardly extending substantially cylindrical member 51 for receiving a center pin by which, as is well known, the center sill is connected to the adjacent car truck. This cylindrical portion is integrally connected to the side walls of the car by a substantially horizontal web or plate portion 52 which is of a width 70 greater than the diameter of the center plate and has portions overlapping portions of the bottom wall of the sill adjoining the center plate. It will, of course, be appreciated that this web member, in addition to connecting the cylindrical

member to the side walls of the sill, integrally connects the latter at a point somewhat above the bottom wall. The end portions of the web 52 are integrally connected to the bottom wall of the sill by substantially vertical transversely extending members 53. These members are also integral with the side walls of the sill and have portions 54 extending above the web 52. It will thus be observed that the lower portions of the center sill adapted for connection to the car trucks are of substantially box shape thereby producing a most rigid construction. To further reinforce the cylindrical center pin receiving member 51 it is provided with a plurality of pairs of rigidifying ribs 55 and 56, respectively, the ribs 55 extending longitudinally of the sill and the ribs 56 extending transversely thereof. The transversely extending ribs 56 integrally connect the cylindrical member to the side walls of the sill and extend on opposite sides of the web 52, the portions of the ribs above the web extending upwardly and being integrally joined with portions of the top wall of the sill adjacent the side walls. The longitudinally extending ribs integrally connect the cylindrical member to the web and to the upwardly extending portions 54 of the transversely extending members 53. These ribs also have portions below the web 52 but instead of being integrally connected to the cylindrical member terminate adjacent the outer edges of the depressed center plate forming portion 50. By forming the portions of the longitudinally and transversely extending ribs which extend below the web 52 in the manner described this portion of the center sill may be easily cast and for this purpose the web 52 is preferably provided with a plurality of core openings 51.

Formed integrally with and projecting laterally from the side walls of the center sill adjacent each of the center plates is a pair of brackets 58 to which the adjacent body bolster is adapted to be secured. Each of the brackets is formed with a substantially horizontal plate portion 59 spaced somewhat above the lower edges of the side walls and preferably disposed in the plane of the horizontal web 52. The plate portions of each of the brackets may be advantageously reinforced by a plurality of downwardly and transversely extending ribs or portions 60, one of the ribs 45 being disposed centrally of the plate and the others being adjacent the marginal edges thereof. The marginal reinforcing portions may conveniently terminate in laterally projecting flanges 61 which incline downwardly from adjacent their outer ends to points outwardly of the adjacent side wall of the sill where they continue in the plane of the bottom wall of the latter. The outer marginal edges of the plate portions may, if desired, be reinforced by a relatively small depending rib 62 and adjacent their inner ends they may be reinforced by triangularly shaped gussets 63 disposed intermediate the main reinforcing ribs 60.

The body bolsters of the car are made of cast metal but instead of forming them as integral castings each is preferably constructed of two sections respectively disposed on opposite sides of the center sill. Each section is provided with a substantially vertical web 64 and with upper and lower flanges 65 and 66, respectively, projecting on opposite sides of the web. To reduce the weight of the bolster sections the webs may be provided with a plurality of apertures which are arranged so as not to impair the strength of the bolster. The upper flange 65 of each bolster sec-

tion is preferably inclined to supportingly cooperate with adjacent inclined floor sheets of the car and it is integrally connected to the web portion of the section by an inclined portion 67 disposed at a substantially right angle to the flange and at an oblique angle to the web. The portions of the lower flanges 66 of the bolster sections between their respective inner ends and the portions to which side bearing wear plates 68 are secured are disposed in substantially horizontal planes and rigidly secured by rivets 69 to the plate portions 59 of brackets 58. The portions of the bottom flange of the bolster sections between the side bearing wear plate 68 and the outer ends of the sections respectively incline upwardly and outwardly as at 70. To rigidify the body bolster sections against bending stresses due to buffing forces transmitted to them from the car center sill the horizontal portions of the lower flanges 66 of the sections are formed with upwardly projecting marginal ribs 71 while the inclined portions of the flanges are formed with downwardly projecting marginal ribs 72.

At their inner and outer ends each of the bolster sections is integrally provided with substantially vertical flanges 73 and 74, respectively, which project on opposite sides of the web 64. The inner flanges 73 are rigidly secured to the adjacent side walls of the center sill by rivets 75 while the outer flanges 74 are rigidly secured to adjacent portions of the side sills and side sheets by rivets 76. Intermediate their ends the upper and lower flanges of the bolster sections are integrally connected by a plurality of truss-like flanges 77 which project on opposite sides of the web 64 and effectively resist and efficiently distribute throughout the bolster the stresses normally imparted thereto by the car body and its contained lading. The truss-like flanges of each bolster section preferably extend upwardly and inwardly from adjacent the lower corner thereof to the upper flange 67, thence downwardly and inwardly toward the portion of the lower flange 66 to which the side bearing wear plate is attached, then, again upwardly to the upper flange 65 and from there downwardly to the adjacent upper corner of the center sill where it merges into the inner flange 73. From the foregoing it will be perceived that each bolster section is in effect formed with an upper chord member of substantially angle shape involving the upper flange 65 and the inclined portion 67, a lower chord member involving the lower flange 66 and adjacent portions of the web, and truss members involving the truss flanges 77 and portions of the web adjoining them.

Adjacent their outer ends each of the bolster sections is preferably provided with an upwardly projecting portion 78, the upper edge of which is formed with an inclined flange 79 which is integrally connected by a substantially vertical flange 80 to the adjacent portion of the upper flange 65 of the section. The upwardly projecting portion 78, together with adjacent end portions of the section, afford convenient means to which the inwardly projecting flanges 9 of adjacent side stakes may be rigidly secured while the inclined flanges 79 of the projections afford supports for inwardly offset downwardly inclined portions of adjacent side sheets of the car.

Each bolster section is also integrally formed with an inwardly projecting upstanding extension overlying the top wall of the center sill. Each extension is formed with an inclined top flange 81 constituting a continuation of the top flange of 75

the bolster section, a substantially vertical plate portion 82 constituting a continuation of the web of the bolster section and an intermediate inclined portion 83 constituting a continuation of the inclined portion 67. To rigidly connect the extensions of the bolster sections to the center sill the latter is integrally provided with an upwardly projection 84 of substantially the same cross sectional shape as the extensions and having portions 85, 86 and 87 respectively corresponding to portions 81, 82 and 83 of the latter. The top flange 85 of the projection 84 preferably underlies the inclined top flanges 81 of the bolster extensions and corresponding portions of the 10 projections and extensions are rigidly connected by a plurality of rivets 88. The center sill projection 84 is conveniently reinforced by a substantially vertical flange 89 which extends downwardly from the upper flange 85 thereof and intersects the top wall of the center sill adjacent its apex and by a plurality of downwardly converging marginal flanges 90 which respectively intersect the center sill adjacent its upper corners. From the foregoing it will be observed that 15 not only are the bolster sections rigidly secured to the brackets 58 and the projection 84 but they are also secured to the side walls of the center sill. In this manner a most rigid connection is obtained between the body bolsters and center 20 sill.

Although the car may be provided with any number of cross bearers for supporting the center sill intermediate the body bolsters I have found that it is necessary to equip a car of the 25 type and character disclosed in the drawings with only two. Each of the cross bearers is of truss form and is preferably constructed as an integral casting extending from one side of the car to the other above the center sill. Each of them is provided with an upper chord member 91 of substantially T-shape having a top flange 92 and a depending flange 93 and with a lower chord member 94 of substantially the same shape having a bottom flange 95 and an upwardly projecting flange 96. At their ends the upper and lower chord members are respectively connected by downwardly diverging truss members 97 of substantially cruciform shape having oppositely projecting flanges 98 and 99, respectively, the flanges 50 98 being substantially vertical and disposed in the plane of the flanges 93 and 96 of the upper and lower chord members. Adjacent their central portions the upper and lower chord members of the cross bearer are integrally connected by a strut member 100 of cruciform configuration having oppositely projecting flanges 101 and 102, the flanges 102 being disposed in the same vertical plane as the vertical flanges of the upper and lower chord member. The chord members 55 are also integrally connected by truss members 103 which diverge upwardly from adjacent the lower end of the strut member 100 to respectively adjacent the points of intersection of the truss members 97 and the upper chord member. The truss members 103 are also of cruciform configuration having oppositely projecting flanges 104 and 105, the latter being disposed in the plane of the other vertical flanges of the cross bearer.

At their outer ends each of the cross bearers is provided with downwardly extending members 106 respectively provided with end flanges conforming to the cross sectional shape of and rigidly secured to the side sills. Moreover, the side stakes adjoining the cross bearer may be rigidly secured to the vertical flanges 98 of the truss 75

members 97 by rivets 107 and so as to provide these truss members with enlarged portions to which the side stakes may be secured the portions of the flanges 98 above the flanges 99 progressively increase in depth from adjacent their upper ends while the portions of the flanges 98 below the flanges 99 progressively decrease a corresponding amount. At their ends the flanges 98 may be conveniently fashioned with offset portions 108 for attachment to adjacent portions of the side sheets of the car. Intermediate portions of the side stakes adjoining the cross bearer may be rigidly connected to the latter by downwardly converging arms 109. To provide the cross bearer with convenient means to which the arms may be attached brackets 110 may be integrally formed therewith adjacent the points of intersection of the top chord member and the truss members 97. Each of these brackets is provided with a substantially vertical portion 111 and a reinforcing flange 112 projecting from opposite sides of the latter. The lower portions of each of the arms 109 is bifurcated and secured to the web 111 of the adjacent bracket in interleaved relation by rivets 113. At their upper ends the arms are respectively provided with enlarged pad portions 114 rigidly secured to the side stakes by rivets 115. From the foregoing it will be perceived that the cross bearers, in addition to being rigidly secured to the side sills, are rigidly connected at vertically spaced points to adjoining side stakes, thus effectively tying together and bracing the car sides.

Adjacent the cross bearer the center sill is integrally provided with a plurality of pairs of members 116 projecting upwardly from the top wall of the sill on opposite sides of flange 95 of the lower chord member 94 of the cross bearer. Each of the members 116 is provided with a substantially vertical web 117 and an inwardly offset substantially horizontal flange 118. If desired, the members 116 may be reinforced by ribs or flanges 119 which intersect the top wall of the center sill adjacent its apex. The central portion of the lower chord member of the cross bearer is interposed between the members 116 and inwardly projecting flanges 118 of the latter overlie adjacent portions of the bottom flange 95 of the chord member. In order that the members 116 may not project a relatively great distance above the top of the center sill to be disposed in interlocking relation with the lower chord member of the cross bearer the portion of the top wall between the members 116 is preferably flattened thereby affording substantially horizontal portions 120. The central portion of the flange 95 of the cross bearer adapted to cooperate with the members 116 is of a width substantially equal to the distance between the webs 117 of the members 116 while other portions of the flange are of a width slightly less than the distance between the inner edges of the flanges 118 of the ribs. By forming the lower flange of the cross bearer in this manner it will be observed that after the cross bearer has been moved transversely of the center sill a sufficient amount to move the enlarged central portion of the flange from between the members 116 the cross bearer is in position to be disconnected from the center sill by being lifted bodily upward. The reverse of this operation is, of course, followed for connecting these parts and it will be appreciated that in building the car the cross bearer and center sill must be connected before any portions of the car sides are assembled. After the car is once assembled, 75

transverse movement of the cross bearers with respect to the center sill is prevented by the car sides thereby preventing accidental disconnection of the center sill and cross bearer. By interlocking these parts of the car underframe in this manner it will be observed that the cross bearers adequately perform their intended function of supporting the center sills without the necessity of rigidly connecting them, as is usually done by rivets.

The end floor sheets 15 of the car which incline downwardly from adjacent the ends of the car to the respective body bolsters may advantageously extend continuously from one side of the car to the other. At their lower edges these sheets are rigidly secured to the inclined top flanges 65 of the body bolsters by rivets 121. Extending downwardly from each of the body bolsters on opposite sides of the center sill are inclined floor sheets 122 which are spaced transversely of the car. These floor sheets extend downwardly below the side sills of the car to form the slope sheets of hoppers designated by the reference letter F.

The outer side edges of the portions of the sheets which extend into the hopper are secured to the outer hopper side sheets 123 while the outer side edges of the portions of the sheets above the side sill are provided with upwardly projecting flanges 124 secured to adjacent car side sheets. To support the inner edge portions of sheets 122 adjacent the center sill the latter is integrally provided with laterally projecting downwardly inclined flanges 125 which underlie the floor sheets. The inner edges of the portions of the sheets which extend below the center sill are secured to their supports by inwardly projecting flanges 126 of the inside hopper sheets 127 which are secured along their upper edges to the side walls of the center sill. The upper portions of flanges 126 are preferably interposed between adjacent portions of the floor sheets and the supporting flanges 125 of the center sill. To eliminate the necessity of offsetting the floor sheets where they first overlap the flanges 126 the lower end portions of flanges 125 are preferably offset downwardly as indicated at 128, a distance equal to the thickness of flanges 126.

The inner edges of the portions of the inclined floor sheets 122 above the center sill are connected by an inclined splice sheet 129. The upper edge of the splice sheet, together with the upper edges of floor sheets 122 underlie the lower edge portions of the end floor sheet 15, being secured to the inclined top flange of the body bolster by the rivets 121. The side edges of the splice sheet overlap the adjacent side edges of floor sheets 122 and are secured thereto by rivets 130. At its lower edge the splice sheet overlaps and is rigidly secured to a flange 131 which is formed integrally with and projects upwardly from the top wall of the center sill. This flange is also formed integrally with and constitutes in effect a continuation of the laterally projecting flanges 125 and it may be suitably reinforced by a rib 132 which projects upwardly from the apex of the top wall. By providing the center sill with flanges to which the adjacent floor sheets and splice sheets may be rigidly secured, the necessity of offsetting the sheets to form attaching flanges is eliminated and a much simpler and yet more rigid construction is produced.

Disposed beneath each of the cross bearers in spaced relation to the lower chord member thereof and on opposite sides of the center sill are transverse or cross ridge sheets 133. Each of

these sheets has downwardly diverging portions to the lower edges of which are respectively secured the door frames 134 and 135 with which the hoppers may be conveniently provided, the numeral 134 designating the door frames of the end hoppers F and 135 designating the door frames of the center hoppers G. The inner edges of the cross ridge sheets overly and are rigidly secured to laterally projecting members 136 formed integrally with the side walls of the center sill. Each of these members is provided with downwardly diverging portions 137 which are inclined longitudinally of the car are respectively disposed in planes parallel with the corresponding diverging portions of the ridge sheets. At 15 their outer ends the ridge sheets are supported by members 138 having downwardly diverging portions 139 underlying the ridge sheets and formed integrally with the depending end portions 106 of the cross bearers. By providing the center 20 sill and the cross bearers with the supporting members 136 and 138 respectively, it will be observed that each of the cross ridge sheets may be conveniently formed of a single sheet which may be easily assembled in the car structure and 25 quickly attached to its associated parts. Moreover, although it is thought unnecessary to connect the cross bearer with the center sill to prevent relative transverse movement of these parts as such movement would be prevented by other 30 parts of the car structure, it will be observed that the cross ridge sheets, in view of the manner in which they are secured to the car, necessarily function so as to prevent this relative transverse movement.

The center sill is preferably reinforced adjacent the points at which it is connected to the cross bearer by a plurality of pairs of internal flanges 140 and 141, respectively. The pairs of flanges designated by the reference numeral 140, 40 extend transversely of the center sill and are spaced longitudinally thereof so as to lie in substantially the planes of the respective webs 117 of the cross bearer connecting members 116. The flanges of each of these pairs are of substantially 45 triangular shape and integrally connect the upper portions of the side walls with adjacent portions of the arched top wall. The pair of flanges designated by the reference numeral 141, also extend transversely of the center sill and are 50 preferably disposed intermediate the pairs of flanges designated 140. Each of flanges 141 is also of triangular shape and integrally connects the bottom wall of the center sill with the lower portions of the adjacent side walls. The upper 55 edges of flanges 141 respectively merge into substantially horizontal ribs 142 which define the lower edges of core openings 143 which may be conveniently formed in the side walls of the center sill below the outwardly projecting ridge 60 sheet supporting members 136.

The center hoppers G of the car are respectively disposed on opposite sides of the center sill in the same manner as the end hoppers F and the inclined floor sheets 144 of the former respectively diverge downwardly on opposite sides of the transverse center axis of the car. The upper portions of the outer side edges of each of the floor sheets is provided with an upwardly projecting flange 145 rigidly secured to the adjacent 70 portions of the adjoining side sill. The lower portion of the outer side edges of each of the floor sheets overlies and is rigidly secured to inwardly flanges 146 of the outer hopper side sheets 147, the latter being secured to the lower flange 75

of the adjacent side sill. Instead of providing the upper inner edge portions of the floor sheets with flanges for attachment to the center sill the latter is preferably integrally formed with members 148 having downwardly diverging portions 149 inclined longitudinally of the car which underlie and are rigidly secured to adjoining portions of the floor sheets. The lower portions of the inner edges of the floor sheets are secured to flanges 150 of the inside hopper sheets 151 in a manner similar to which the lower portions of the outer edges are secured to the outside hopper sheets, the inside hopper sheets, of course, being secured to the side walls of the center sill.

15 The inclined portions 149 of the members 148 extend upwardly to the apex of the arched top wall of the center sill and are integrally connected by a substantially horizontal portion 152 which in effect forms a part of the top wall. 20 The portions of the top wall of the center sill immediately adjacent the horizontal portion 152 are inclined longitudinally of the car being respectively disposed in the planes of the adjoining inclined portions 149 and intersecting the transversely inclined portions of the top wall in downwardly inclined diagonally extending lines.

25 The upper edges of the floor sheets 144 terminate in substantially horizontal flanges 153 which are overlappingly secured to horizontal flanges 154 of transversely extending members 155 respectively disposed on opposite sides of the center sill. The inner edges of the horizontal flanges of the transverse members underlie and are rigidly connected to the horizontal portions 152 of the center sill while the inner portions of the horizontal flanges of the floor sheets overlie and are rigidly secured to these portions. At their outer ends each of the transverse members 144 is rigidly secured to a bracket 156 mounted on the adjacent side wall of the car. Each of these brackets is formed with an angle shaped upper portion having flanges 157 and 158, respectively, secured to adjacent portions of the adjoining car side sheet and side stake and with a lower plate portion 159 overlappingly secured to the inner face of the upper flange 3 of the adjacent side sill. The plate portion is integrally formed with an inwardly projecting flange having a substantially horizontal portion 160 and oppositely extending downwardly diverging portions 161. The horizontal portion 160 affords a convenient means to which the arched flange 154 of the adjacent transversely extending member 155 may be secured while the diverging portions 161 afford convenient means for supporting the upper outer corners of the inclined floor sheets 144. It will, of course, be observed that flange 154 underlies the horizontal portion 160 of the bracket while the floor sheets overlie the downwardly diverging portions of the latter. By integrally providing the center sill with the laterally projecting members 144 to which the floor sheets of the hoppers G and the transversely extending members 145 may be rigidly secured and by connecting these parts in the manner described it will be appreciated that an extremely rigid and yet simple construction is produced.

70 The center sill may be conveniently reinforced adjacent the portions to which the floor sheets 144 are connected by a pair of substantially vertical, preferably triangularly shaped, reinforcing ribs or flanges 162. Each of these flanges integrally connects the bottom wall of the center sill with the lower portion of the adjacent side wall. At their upper edges the flanges 162 re-

spectively merge into reinforcing ribs 163 surrounding core openings 164 with which the side walls may be conveniently provided.

If desired, the center sill may be integrally provided at any suitable place, as for instance, adjacent one of the body bolsters, with a pad or bracket 165 on which an air brake cylinder may be mounted. The pad may be advantageously formed with a substantially horizontal plate portion 166 adjacent the upper edge of the adjoining side wall of the sill and with downwardly extending marginal reinforcing flanges 167. The center sill may also be conveniently integrally formed adjacent its opposite ends with brackets 168 to which diagonal braces (not shown) may be respectively secured. These brackets are also preferably formed with horizontal plate portions 169 and with substantially vertical downwardly extending reinforcing flanges 170.

20 By providing a hopper car with a cast steel center sill of the form illustrated, an extremely rigid car construction may be produced and one in which a minimum number of rivets are employed. Moreover, the construction of the sill is such that adjoining parts of the car may be 25 easily and most rigidly secured to it and the car construction as a whole is greatly simplified.

I claim:

1. A railway car having a cast metal center sill involving integrally connected substantially 30 vertical side walls, an arched top wall, and a substantially horizontal bottom wall, said side and top walls extending from one end of the sill to the other and said bottom wall terminating inwardly of the ends of the sill. 35

2. A railway car having a cast metal center sill, and body bolsters rigidly secured to the latter inwardly of its ends, said sill being provided with integrally connected side, top and bottom walls, said bottom wall extending from adjacent the 40 portion of the sill to which one of said bolsters is secured to adjacent the portion thereof to which the other of said bolsters is secured and terminating adjacent said portions, said side walls being respectively provided intermediate said bolster and 45 the respectively adjacent ends of the sill with laterally projecting flanges which terminate adjacent the ends of said bottom walls.

3. A railway car having a cast metal center sill, provided with integrally connected side, top 50 and bottom walls, said bottom walls terminating inwardly of the ends of the sill, said side walls being integrally provided with laterally projecting flanges respectively extending from adjacent the ends of the sill to the ends of the bottom 55 wall and terminating adjacent said ends.

4. A railway car having a cast metal center sill, and body bolsters rigidly secured to the latter inwardly of its ends, said sill being provided with integrally connected side, top and bottom walls, 60 said side and top walls extending from one end of the sill to the other and said top wall being arched transversely of the sill, said bottom wall extending from adjacent the portion of the sill to which one of said bolsters is secured to adjacent the portion thereof to which the other of said bolsters is secured, said side walls being integrally provided adjacent their lower edges with outwardly projecting flanges extending from adjacent the ends of said bottom wall to adjacent 65 the adjoining ends of the sill.

5. A railway car having a cast metal center sill extending from one end of the car to the other and provided with integrally connected side, top and bottom walls, and body bolsters rigidly 70

- secured to said sill inwardly of the ends of the latter, said top wall having downwardly converging portions, said bottom wall extending from adjacent the portion of the sill to which one of 5 said bolsters is secured to adjacent the portion thereof to which the other of said bolsters is secured, said side walls being integrally provided adjacent their lower edges with outwardly projecting substantially horizontal flanges extending 10 from adjacent the ends of the bottom wall to adjacent the adjoining ends of the sill.
6. A railway car having a cast metal center sill provided with integrally connected side and top walls, said top wall being arched intermediate 15 the ends of the sill and merging into substantially horizontal portions adjacent said ends.
7. A railway car having a cast metal center sill provided with integrally connected side and top walls, said top wall being provided adjacent its 20 ends with substantially horizontal portions and inwardly of its ends with downwardly diverging portions inclined transversely of the car, adjacent portions of said horizontal and inclined portions being respectively connected by portions inclined longitudinally of the car.
8. A railway car having a cast metal center sill provided with spaced side walls and a top wall integrally connecting the latter, substantially vertical members projecting inwardly from the 25 respective side walls and formed integrally with the latter and said top wall, said members being adapted to cooperate with followers of a draft gear, and means for reinforcing said vertical members comprising portions extending longitudinally of the sill and formed integrally with the side walls thereof.
9. A railway car having a cast metal center sill involving spaced side walls, and a top wall integrally connecting the side walls, each of said side 30 walls being integrally provided with a substantially vertical member the upper portion of which is integral with the top wall, said members being adapted to cooperate with the follower of a draft gear, and a plurality of channel-shaped members formed integral with each side wall and extending longitudinally of the sill for reinforcing the adjacent vertical member.
10. A railway car having a cast metal center sill provided with integrally connected side and top walls, said side walls being respectively integrally provided with inwardly projecting transversely extending members adapted to cooperate with the followers of a draft gear, the upper portions of 35 said members merging into and being formed integrally with said top wall, said side walls being also integrally provided with inwardly projecting longitudinally extending members for reinforcing said transversely extending members, each of said longitudinally extending members being of channel shape and the webs of said channel shaped members being disposed in a vertical plane inclined with respect to the said side walls.
11. A railway car having a cast metal center sill provided with side walls, and angularly shaped members for integrally connecting said side walls, said members being respectively disposed adjacent the portions of the sill to which the car trucks are adapted to be pivotally associated.
12. A railway car having a cast metal center sill provided with integrally connected side and top walls, and angularly shaped members spaced below said top wall and having substantially horizontal and vertical portions integrally connecting said side walls, said members being respectively disposed adjacent the portions of the sill to

which the car trucks are adapted to be pivotally associated.

13. A railway car having a cast metal center sill provided with integrally connected side and top walls, and channel shaped members integrally connecting said side walls, said members being respectively disposed adjacent the portions of the sill to which the car trucks are adapted to be pivotally associated. ⁵

14. A railway car having a cast metal center sill provided with integrally connected side and top walls, and channel shaped members integrally connecting said side walls disposed adjacent the portions of the sill to which the car trucks are adapted to be pivotally associated, each 15 of said channel shaped members having a substantially horizontal web and substantially vertical flanges.

15. A railway car having a cast metal center sill provided with integrally connected side and 20 top walls, means rigid with the said side walls for cooperating with draft gear followers, and members disposed adjacent said means and intermediate the upper and lower edges of the side walls for integrally connecting the side walls. ²⁵

16. A railway car having a cast metal center sill provided with integrally connected side and top walls, means rigid with said side walls for cooperating with draft gear followers, and members disposed adjacent said means for integrally connecting said side walls, each of said members being of angular shape and having substantially horizontal and vertical portions. ³⁰

17. A railway car having a cast metal center sill provided with spaced side walls and a top 35 wall integrally connecting the latter, each of said walls extending substantially continuously from one end of the sill to the other, portions of the top wall adjacent the ends of the sill being arched and extending above the upper edges of the side 40 walls, each of said arched portions of the top wall and the adjacent portions of the side walls forming a pocket for receiving a draft gear.

18. A railway car having a cast metal center sill provided with spaced side walls and a top 45 wall integrally connecting the side walls, each of said walls extending substantially continuously from one end of the sill to the other, portions of the top wall adjacent the ends of the sill being provided with upwardly converging portions inclined transversely of the car and respectively intersecting above the upper edges of the side walls, said upwardly converging portions of the top wall and the respectively adjacent portions of the side walls forming pockets for receiving draft 55 gears.

19. A railway car having a cast metal center sill provided with spaced side walls and a top wall integrally connecting the latter, each of said walls extending substantially continuously from 60 one end of the sill to the other, portions of the top wall adjacent the ends of the sill being arched and extending above the upper edges of the side walls, each of said arched portions of the top walls and the adjacent portions of the side walls 65 forming a pocket for receiving a draft gear, the portions of the side walls forming said pocket being respectively provided adjacent their lower edges with outwardly projecting flanges.

20. A railway car having a cast metal center 70 sill provided with integrally connected side and top walls, a center plate formed integrally with said sill, a web spaced above said center plate and integrally connecting said side walls, a hollow substantially cylindrical member formed in-

tegrally with said center plate and said web, said cylindrical member extending upwardly above said web, and a plurality of ribs integrally connecting the upwardly projecting portion of 5 said cylindrical member and said web.

21. A railway car having a cast metal center sill provided with integrally connected side and top walls, a center plate formed integrally with said sill, a hollow substantially cylindrical member formed integrally with and extending upwardly from said center plate, a substantially horizontal web disposed intermediate said center plate and said top wall integrally connecting said cylindrical member and said side walls, said web being also disposed below the upper end of the cylindrical member and a plurality of substantially vertical ribs integrally connecting said web and center plate.

22. A railway car having a cast metal center sill provided with integrally connected side and top walls, a center plate formed integrally with said sill, a hollow substantially cylindrical member formed integrally with the center plate and projecting upwardly therefrom, a substantially horizontal web member spaced above said center plate and integrally connecting said cylindrical member and side walls, and a plurality of transversely extending substantially vertically disposed ribs, each of said ribs having portions disposed above and below said web, the portions below said web integrally connecting the latter to the center plate and the portions above said web integrally connecting the latter with adjacent portions of the side and top walls of the sill.

23. A railway car having a cast metal center sill provided with integrally connected side, top and bottom walls, a center plate formed integrally with said bottom wall, a hollow substantially cylindrical member formed integrally with the center plate and projecting upwardly therefrom, a substantially horizontal web integrally connecting said cylindrical member and said side walls, substantially vertical transversely extending members integrally connecting said web and bottom wall, and longitudinally extending ribs integrally connecting portions of the web adjacent said transversely extending members with said cylindrical member.

24. A railway car having a cast metal center sill provided with integrally connected side, top and bottom walls, a center plate formed integrally with said bottom wall, a hollow substantially cylindrical member formed with the center plate and projecting upwardly therefrom, a substantially horizontal web integrally connecting said cylindrical member and said side walls, and substantially vertical transversely extending members integrally connecting said web and bottom wall, said members having portions extending upwardly above said web, longitudinally extending ribs integrally connecting the upwardly extending portions of said transversely extending members with said cylindrical member, and substantially vertical transversely extending ribs integrally connecting said web, cylindrical portion and side walls.

25. A railway car comprising a body bolster, and a center sill involving side walls, and top and bottom walls integrally connecting the side walls, each of said side walls being provided adjacent its lower portion with a laterally projecting bracket, said body bolster being rigidly secured to said side walls of the center sill and to the said brackets in overlapping relation thereto.

26. A railway car having a cast metal center

sill provided with spaced side walls, each of said walls being integrally provided adjacent its lower portion with a laterally projecting bracket affording means to which a body bolster may be attached, said brackets respectively having plate 5 portions and rigidifying portions along the side marginal edges of the latter.

27. A railway car comprising a body bolster, and a center sill provided with spaced side walls respectively formed with laterally projecting 10 brackets, each of said brackets having a substantially horizontal plate portion and downwardly extending rigidifying portions, said body bolster being rigidly secured to said horizontal plate portions of the brackets and to said side walls of the 15 center sill.

28. A railway car having a center sill provided with spaced side walls integrally formed with laterally projecting brackets respectively affording means to which a body bolster may be attached, each of said brackets being provided with downwardly extending rigidifying portions respectively terminating in laterally projecting flanges.

29. A railway car having a cast metal center 25 sill provided with spaced side walls respectively formed with laterally projecting brackets affording means to which a body bolster may be rigidly secured, each of said brackets having a substantially horizontal plate portion to which the body 30 bolster is adapted to be secured, each of said plate portions being disposed in a plane intersecting the adjacent side wall of the sill between its upper and lower edges.

30. A railway car having a center sill involv- 35 ing side walls, top and bottom walls integrally connecting the side walls, and a bracket formed integrally with and projecting laterally from each of said side walls affording means to which a body bolster may be rigidly secured, each of said 40 brackets having a plate portion disposed in a substantially horizontal plane intersecting the adjacent side wall of the sill intermediate said top and bottom walls.

31. A railway car having a center sill involv- 45 ing side walls, top and bottom walls integrally connecting the side walls, a bracket formed integrally with and projecting from each of said side walls affording means to which a body bolster may be rigidly secured, each of said brackets 50 being provided with a substantially horizontal plate portion, and a web extending between and integrally connecting said side walls above said bottom wall, said web being disposed in substantially the same plane as the plate portions of 55 said brackets.

32. A railway car having a cast metal center sill involving side walls, top and bottom walls integrally connecting said side walls, a center plate formed integrally with said bottom wall, 60 brackets respectively formed integrally with and projecting laterally from said side walls affording means to which a body bolster may be secured, each of said brackets having a substantially horizontal plate portion spaced above the plane of 65 said bottom wall, and a web overlying said center plate and integrally connecting said side walls, said web being disposed in the plane of said plate portions of the brackets.

33. A railway car having a center sill integral- 70 ly provided with an upstanding projection adapted to be rigidly secured to a body bolster for attachment to a body bolster, said projection having a web portion and an inclined top flange, the latter projecting on opposite sides of the web and 75

being integrally connected thereto by a portion extending at an angle therewith.

34. A railway car having a center sill integrally provided with an upstanding projection for attachment to a body bolster, said projection being provided with downwardly converging rigidifying flanges.

35. A railway car having a cast metal center sill involving side walls, an arched top wall integrally connecting said side walls, said top wall being integrally formed with an upstanding projection for attachment to a body bolster.

36. A railway car having a center sill involving side walls, an arched top wall integrally connecting the side walls, and an upstanding projection formed integrally with said top wall for attachment to a body bolster, said projection being provided with a substantially vertical reinforcing flange intersecting said top wall adjacent the apex thereof.

37. A railway car having a center sill involving side walls, a top wall integrally connecting the side walls, and an upstanding projection formed integrally with said top wall for attachment to a body bolster, said projection being provided with a substantially vertical flange disposed in a plane intermediate said walls and with downwardly converging flanges intersecting said top wall adjacent said side walls.

38. A railway car having a center sill provided with spaced integrally connected side walls, laterally projecting brackets respectively formed integrally with said side walls, and an upstanding projection formed integrally with the sill, said brackets and projection being adapted to be secured to a body bolster.

39. In a railway car, in combination, a center sill integrally provided with an upwardly projecting portion and a plurality of oppositely extending laterally projecting portions, and a body bolster rigidly secured to said upwardly and laterally projecting portions.

40. In a railway car, in combination, a center sill having spaced side walls, a top wall integrally connecting said side walls, said side walls being respectively integrally formed with oppositely extending laterally projecting brackets and said top wall being integrally provided with an upwardly extending projection, and a body bolster having portions rigidly secured to said brackets and said projection.

41. In a railway car, in combination, a center sill having spaced side walls provided with oppositely extending laterally projecting portions, an upwardly projecting portion rigid with the center sill, and a body bolster having portions respectively secured to said side walls and to said laterally and upwardly projecting portions.

42. In a railway car, in combination, a center sill provided with spaced integrally connected side walls, each of said side walls being provided with an outwardly projecting bracket, and a body bolster comprising a plurality of sections respectively disposed on opposite sides of the center sill, one of said bolster sections being rigidly secured to one of said brackets and the adjacent side wall of the sill and the other of said bolster sections being rigidly secured to the other of said brackets and the side wall adjacent thereto.

43. In a railway car, in combination, a center sill provided with spaced integrally connected side walls, each of said side walls being provided with an outwardly projecting bracket, and a body bolster comprising a plurality of sections respectively disposed on opposite sides of the

center sill, each bolster section having end and bottom walls respectively secured to one of said side walls and the bracket adjacent thereto.

44. In a railway car, in combination, a center sill provided with spaced integrally connected side walls, each of said side walls being integrally provided with an outwardly projecting bracket having a substantially horizontal plate portion, and a body bolster comprising a plurality of sections respectively disposed on opposite sides of the center sill, one of said bolster sections being rigidly secured to the plate portion of one of said brackets and the adjacent side wall of the sill and the other of said sections being rigidly secured to the plate portion of the other of said brackets and the side wall adjacent thereto.

45. In a railway car, in combination, a floor, a center sill disposed below the floor and integrally provided with an upstanding projection, and a body bolster comprising a plurality of sections respectively disposed on opposite sides of the center sill, each of said bolster sections being provided with an extension interposed between the top of the center sill and the car floor, said extensions being secured to said upstanding projection in overlapping relation thereto.

46. In a railway car, in combination a center sill having spaced side walls, a top wall integrally connecting said side walls, each of said side walls being provided with a laterally extending bracket and said top wall being provided with an upwardly projecting portion, and a body bolster comprising a plurality of sections respectively disposed on opposite sides of the center sill, said sections being respectively secured to said brackets and each being provided with an extension overlappingly secured to said upwardly projecting portion.

47. In a railway car, in combination, a cast metal center sill having integrally connected top and side walls, laterally projecting brackets respectively formed integrally with said side walls, each of said brackets being provided with a substantially horizontal plate portion disposed in a plane intermediate the upper and lower edges of said side walls, the top wall being integrally provided with an upwardly projecting portion, and a body bolster comprising a plurality of sections respectively disposed on opposite sides of the center sill, said bolster sections respectively having horizontal portions and plate-like extensions respectively secured in overlapping relation to said brackets and said upwardly projecting portion of the center sill.

48. In a railway car, in combination, a center sill having spaced side walls, said side walls being respectively provided with laterally projecting portions, a body bolster comprising a plurality of sections respectively disposed on opposite sides of the center sill, each of said bolster sections being provided with a substantially horizontal portion rigidly secured to the adjacent laterally extending portion of the center sill and an upwardly and outwardly inclined portion extending from said horizontal portion to adjacent the end of the section, said horizontal portions of the bolster sections being respectively provided with upwardly projecting marginal portions and said inclined portions of the bolster sections being respectively provided with downwardly projecting marginal portions.

49. In a railway hopper car, the combination with an inclined floor sheet, of a center sill involving substantially vertical side walls and an arched top wall integrally connecting the side

- walls, said top wall being integrally provided with an upwardly extending portion affording means to which said floor sheet may be rigidly secured.
50. In a railway hopper car, the combination with inclined floor sheets, of a center sill having spaced substantially vertical side walls and an arched top wall integrally connecting the latter, said side and top walls being integrally provided with projecting portions for supportingly cooperating with adjacent portions of said inclined floor sheets.
51. In a railway car, in combination, a center sill having spaced side walls, a body bolster rigidly secured to the sill, slope sheets extending downwardly from the bolster on opposite sides of said sill, and laterally projecting portions formed integrally with the side walls of the sill for supportingly cooperating with adjacent portions of the slope sheets.
52. In a railway car, in combination, a center sill, a body bolster secured to the center sill, spaced slope sheets extending downwardly from the bolster on opposite sides of the center sill, a downwardly extending splice sheet connecting said slope sheets, and means formed integrally with said center sill affording means to which said slope and splice sheets are rigidly secured.
53. In a railway car, in combination, a center sill having integrally connected top and side walls, a body bolster secured to the center sill, spaced slope sheets extending downwardly from the bolster on opposite sides of said center sill, a laterally projecting portion formed integrally with each side wall of the center sill for supportingly cooperating with the adjacent slope sheet, a splice sheet extending downwardly from the bolster connecting said slope sheets, and an upwardly projecting portion formed integrally with the top wall of the center sill to which said splice sheet is rigidly secured.
54. In a railway car, in combination, a center sill having spaced side walls, a body bolster secured to said sill, slope sheets extending downwardly from the bolster on opposite sides of the center sill, a laterally extending portion formed integrally with each side wall of the center sill underlying and rigidly secured to the adjacent slope sheet, and hopper side sheets rigidly secured to said center sill, each of said hopper side sheets being provided with an outwardly extending flange having a portion interposed between the adjacent slope sheet and the adjacent laterally extending portion of the sill.
55. In a railway car, in combination, a center sill having integrally connected side and top walls, a bolster secured to said center sill, spaced slope sheets extending downwardly from the bolster on opposite sides of the center sill, laterally projecting flanges formed integrally with the side walls of the sill respectively underlying and supporting adjacent portions of the slope sheets, a splice sheet extending downwardly from the bolster having portions overlying and secured to said slope sheets, and an upwardly projecting flange formed integrally with the top wall of the center sill and underlying and supporting said splice sheet, said upwardly projecting flange connecting and constituting a continuation of said laterally projecting flanges.
56. In a railway hopper car, in combination, a center sill and transversely extending ridge sheets disposed on opposite sides of the center sill, the center sill being integrally provided with portions for supporting adjacent portions of said ridge sheets.
57. In a railway hopper car, in combination, a center sill, transversely extending ridge sheets disposed on opposite sides of the center sill, said center sill being rigidly provided with laterally projecting inclined flanges for supportingly cooperating with said ridge sheets.
58. In a railway hopper car, in combination, a center sill, transverse ridge sheets disposed on opposite sides of the center sill, each side of the center sill being integrally provided with downwardly diverging portions for supportingly cooperating with said ridge sheets.
59. In a railway hopper car, in combination, a center sill having spaced side walls, and transverse ridge sheets disposed on opposite sides of the center sill, each side wall of the sill being integrally provided with laterally projecting downwardly diverging portions for supportingly cooperating with said ridge sheets.
60. In a railway hopper car, in combination, a center sill having integrally connected side and top walls, transverse ridge sheets respectively disposed on opposite sides of the center sill, each side wall of the center sill being integrally provided with downwardly diverging portions underlying adjacent portions of the adjacent ridge sheet for supportingly cooperating with the latter.
61. In a railway hopper car, in combination, a center sill involving spaced side walls and an arched top wall integrally connecting said side walls, and transverse ridge sheets disposed on opposite sides of the center sill, each side wall of the center sill being integrally provided with a member having downwardly diverging portions for supportingly cooperating with adjoining portions of the adjacent ridge sheets, the diverging portions of each of said members intersecting below the upper portion of said arched top wall.
62. A center sill for railway hopper cars comprising spaced side walls, a top wall integrally connecting the side walls and provided with downwardly diverging portions, each of said side walls being integrally provided with laterally projecting downwardly diverging flanges, the flanges on each side wall intersecting adjacent the point of juncture of said side wall and the top wall.
63. A center sill for a railway hopper car having integrally connected side and top walls, said top wall being provided with portions inclined transversely of the car, said side walls being respectively provided with laterally projecting members adapted to supportingly cooperate with cross ridge sheets of the car, each of said members having portions inclined longitudinally of the car.
64. A center sill for railway hopper cars having a top wall provided with portions inclined transversely of the car, and members formed integrally with and projecting laterally from the sill having portions inclined longitudinally of the car.
65. A center sill for railway hopper cars having a top wall provided with portions inclined transversely of the car, and members projecting laterally from the sill, each of said members having downwardly diverging portions inclined longitudinally of the car.
66. In a railway car, in combination, a center sill, and a cross bearer for supporting the center sill, the latter being rigidly provided with portions disposed in interlocking relation with portions of the cross bearer.

39

50

70

75

67. In a railway car, in combination, a center sill, a cross bearer extending from one side of the car to the other above the center sill, and a pair of upwardly projecting members rigid with the center sill arranged in interlocking relation with the cross bearer.
68. In a railway car, in combination, a center sill, and a cross bearer, said sill being provided with an upwardly projecting member having an offset portion overlying an adjacent portion of the cross bearer for interlocking the latter with the sill.
69. In a railway car, in combination, a center sill, a cross bearer, and members rigid with the center sill projecting upwardly therefrom on opposite sides of the cross bearer and disposed in interlocking relation therewith.
70. In a railway car, in combination, a center sill, a cross bearer extending from one side of the car to the other above the center sill, and members rigid with the center sill and projecting upwardly therefrom on opposite sides of the cross bearer, each of said members having an offset portion disposed in overlapping relation with an adjacent portion of the cross bearer.
71. In a railway car, in combination, a center sill, and a cross bearer, said center sill being rigidly provided with upwardly projecting web portions disposed on opposite sides of the lower portion of the cross bearer, said webs respectively having flanges projecting toward each other and disposed in overlapping relation with the lower portion of the cross bearer.
72. In a railway car, in combination, a center sill, a cross bearer extending from one side of the car to the other above the center sill, a pair of members respectively having webs extending transversely of the center sill and disposed on opposite sides of the cross bearer, each of said webs having a laterally offset portion disposed in interlocking relation with an adjacent portion of the cross bearer.
73. In a railway car, in combination, a center sill, a cross bearer disposed above the center sill, the latter being integrally provided with members disposed in interlocking relation with said cross bearer.
74. In a railway car, in combination, a center sill involving side walls and an arched top wall integrally connecting the side walls, a cross bearer disposed above the center sill, said arched top wall being integrally provided with portions overlying adjacent portions of said cross bearer.
75. In a railway car, in combination, a center sill having spaced side walls and an arched top wall integrally connecting said side walls, said top wall being provided with a recessed portion, a cross bearer having a portion disposed within said recess, and means rigid with said top wall adjacent the recess having portions overlying adjacent portions of the cross bearer.
76. In a railway car, in combination, a center sill having spaced side walls and an arched top wall integrally connecting said side walls, the upper portion of said top wall being provided with a recess, a cross bearer having a portion disposed within said recess, and means formed integrally with said arched top wall adjacent said recess and projecting upwardly on opposite sides of the cross bearer, said means being provided with portions overlying adjacent portions of the cross bearer.
77. In a railway car, in combination, a center sill, a cross bearer extending from one side of the car to the other above the center sill, said cross bearer being provided with a flange adjacent its lower portion, and brackets rigid with said center sill and respectively disposed adjacent opposite edges of said flange of the cross bearer, each of said brackets being provided with a portion overlying an adjacent portion of the upper surface of said flange.
78. In a railway car, in combination, a center sill, a cross bearer disposed above the center sill and provided adjacent its lower portion with a flange, and brackets rigid with the center sill and respectively disposed on opposite sides of said flanges, said brackets being respectively provided with portions overlying adjacent portions of said flange, the portion of the flange between the brackets being of greater width than adjacent portions of the flange.
79. In a railway car, in combination, a center sill, a cross bearer extending from one side of the car to the other above the center sill and provided with a substantially horizontal flange, said flange being enlarged adjacent its central portion, and brackets rigid with the center sill and projecting upwardly on opposite sides of said flange of the cross bearer, said brackets being respectively provided with portions overlying the enlarged central portion of said flange.
80. In a railway car, in combination, a center sill, a cross bearer disposed above the center sill and provided with upper and lower chord members, a substantially vertical strut member integrally connecting the central portions of said chord members, and means rigid with the center sill overlying the central portion of said lower chord member.
81. In a railway car, in combination, a center sill, a cross bearer disposed above the center sill and provided with upper and lower chord members, a substantially vertical strut member integrally connecting the central portions of said chord members, said lower chord member being provided with a substantially horizontal bottom flange, and members rigid with said center sill and respectively disposed on opposite sides of said bottom flange, each of said members having a portion overlying an adjacent portion of the bottom flange.
82. In a railway car, in combination, a center sill, a cross bearer disposed above the center sill and provided with upper and lower chord members, a substantially vertical strut member integrally connecting the upper and lower chord members, and truss members diverging upwardly from the lower portion of said strut member also integrally connecting said chord members, and means rigid with the center sill for connecting said lower chord member thereto.
83. In a railway car, in combination, a center sill, a cross bearer extending from one side of the car to the other above the center sill and connected to the latter, and cross ridge sheets disposed on opposite sides of the center sill beneath the cross bearer in spaced relation to the lower portion of the latter.
84. In a railway car, in combination, a center sill, a cross bearer extending from side to side of the car above the center sill, and cross ridge sheets respectively disposed on opposite sides of the center sill, each of said sheets being disposed beneath the cross bearer in spaced relation thereto and provided with downwardly diverging portions.
85. In a railway car, in combination, a center sill, a cross bearer disposed above the center sill and provided with a lower chord member ex- 75

tending from one side of the car to the other, and cross ridge sheets respectively disposed on opposite sides of the center sill, each of said ridge sheets being disposed beneath said cross bearer in spaced relation to the lower chord member thereof.

86. In a railway car, in combination, a center sill, a cross bearer connected with the center sill and extending from one side of the car to the other above said sill, and cross ridge sheets respectively disposed on opposite sides of the center sill, said ridge sheets being disposed beneath the cross bearer in spaced relation thereto and having downwardly diverging portions, said center sill being rigidly provided with portions for supportingly cooperating with adjacent portions of said ridge sheets.

87. In a railway car, in combination, side sills, a center sill, a cross bearer connected to the center sill and extending from one side of the car to the other above the latter, cross ridge sheets respectively disposed on opposite sides of the center sill, said ridge sheets being spaced beneath the lower portion of the cross bearer, and means rigid with said side and center sills for supportingly cooperating with adjacent portions of the ridge sheets.

88. In a railway car, in combination, a center sill, a cross bearer connected to the center sill and extending from one side of the car to the other above the sill, cross ridge sheets respectively disposed on opposite sides of said center sill and in spaced relation to the lower portion of the cross bearer, each of said ridge sheets being provided with downwardly diverging portions, and laterally projecting portions integral with said center sill for supporting adjacent portions of said ridge sheets.

89. In a railway car, in combination, a center sill, a cross bearer extending from one side of the car to the other above the center sill, cross ridge sheets respectively disposed on opposite sides of the center sill and respectively having downwardly diverging portions, said ridge sheets being disposed in spaced relation to the bottom of said cross bearer, and a pair of laterally projecting downwardly diverging flanges formed integrally with the center sill for respectively supporting adjacent portions of said ridge sheets.

90. In a railway car, in combination, a center sill, a cross bearer connected to the center sill and extending from one side of the car to the other, cross ridge sheets respectively disposed on opposite sides of the center sill in spaced relation to the underside of the cross bearer, said center sill being provided with outwardly projecting portions for respectively supporting the inner end portions of said cross ridge sheets and said cross bearer being provided with portions for respectively supporting the outer end portions of said sheets.

91. In a railway car, in combination, a center sill, a cross bearer connected to the center sill and extending from one side of the car to the other above the sill, cross ridge sheets respectively disposed on opposite sides of the center sill in spaced relation to the underside of the cross bearer, each of said cross ridge sheets being provided with integrally connected downwardly diverging portions, said center sill being integrally provided with outwardly projecting downwardly diverging flanges for respectively supporting the inner ends of said ridge sheets and said cross bearer being integrally provided with inwardly projecting downwardly diverging flanges for re-

spectively supporting the outer ends of said cross ridge sheets.

92. In a railway car, in combination, a center sill comprising integrally connected side and top walls, a cross bearer connected to the center sill and extending above the latter from one side of the car to the other, said center sill being integrally provided with a plurality of internal strengthening ribs adjacent the point of connection thereof to the cross bearer.

93. In a railway car, in combination, a center sill comprising integrally connected side and top walls, a cross bearer disposed above the center sill, a pair of members rigid with the center sill for connecting the cross bearer thereto, and a plurality of internal strengthening ribs formed integrally with the side and top walls of the center sill, said ribs being respectively disposed adjacent said rigid members.

94. In a railway car, in combination, a center sill having integrally connected side and top walls, a cross bearer disposed above the center sill, and a plurality of members rigid with said center sill and projecting upwardly therefrom on opposite sides of the cross bearer, each of said members being provided with a substantially vertical web portion and an offset portion overlying an adjacent portion of the cross bearer, and a plurality of internal strengthening ribs formed integrally with the top and side walls of said sill and respectively disposed in the planes of said web portions.

95. In a railway car, in combination, a center sill comprising integrally connected side and top walls, a cross bearer disposed above the center sill, and means rigid with the center sill for connecting the cross bearer thereto, said center sill being provided with a plurality of internal strengthening ribs integrally connecting the upper portions of said side with said top wall.

96. In a railway car, in combination, a center sill comprising integrally connected side and top walls, a cross bearer above the center sill, and means rigid with the center sill for connecting the cross bearer thereto, and a plurality of pairs of internal strengthening ribs formed integrally with the center sill, the ribs of each pair respectively integrally connecting the upper portions of said side walls with adjacent portions of the top wall.

97. In a railway car, in combination, a center sill having integrally connected side and top walls, a cross bearer disposed above and connected to said center sill, said center sill being integrally provided with a plurality of internal strengthening ribs adjacent the point of its connection to the cross bearer, each of said strengthening ribs being of substantially triangular shape.

98. In a railway car, in combination, a center sill having integrally connected side and top walls, a cross bearer disposed above and connected to said center sill, the latter being provided with a plurality of pairs of internal strengthening ribs adjacent the point of its connection to the cross bearer, the ribs of each pair being substantially triangular and respectively connecting the upper portions of said side walls with adjacent portions of the top wall.

99. In a railway car, in combination, a center sill having integrally connected side, top and bottom walls, a cross bearer disposed above the center sill, members rigid with the center sill for connecting the cross bearer thereto, rib means integrally connecting the upper portions of the side walls and adjacent portions of the top wall,

and rib means integrally connecting the lower portions of the side walls and adjacent portions of the bottom wall.

100. In a railway car, in combination, a center sill having integrally connected side, top and bottom walls, a cross bearer disposed above the center sill, members rigid with the center sill and projecting upwardly therefrom on opposite sides of the cross bearer, said members respectively having portions overlying adjacent portions of the cross bearer, said center sill being provided with longitudinally spaced internal ribs respectively adjacent said members, said ribs integrally connecting the upper portions of the side walls and the adjacent portions of the top wall, and rib means intermediate said longitudinally spaced ribs for integrally connecting the lower portions of the side walls and adjacent portions of the bottom wall.
101. In a railway car, in combination, a center sill having integrally connected side, top and bottom walls, a cross bearer disposed above the center sill, members rigid with the center sill and projecting upwardly therefrom on opposite sides of the cross bearer for connecting the latter to the sill, a plurality of pairs of longitudinally spaced internal ribs for rigidifying said sill adjacent said members, the ribs of each pair respectively integrally connecting the upper portions of said side walls and adjacent portions of the top wall, and a pair of ribs disposed intermediate said first-named pairs of ribs, said last-named pair of ribs integrally connecting the lower portions of said side walls and adjacent portions of the bottom wall.
102. In a railway car, in combination, a center sill having integrally connected side, top and bottom walls, a cross bearer disposed above the center sill, members formed integrally with said sill projecting upwardly therefrom on opposite sides of the cross bearer for connecting the latter to the sill, a plurality of triangularly shaped internal strengthening ribs respectively disposed adjacent said members, said ribs integrally connecting the upper portions of said side walls and adjacent portions of the top wall, and internal strengthening ribs integrally connecting the lower portions of said side walls and adjacent portions of the bottom wall, said second-named ribs being disposed intermediate said first-named ribs.
103. In a railway car, in combination, a center sill, a pair of downwardly diverging inclined floor sheets disposed on each side of the center sill, and members respectively rigid with and projecting laterally from the sides of the center sill, each of said members having diverging portions for supportingly cooperating with adjacent portions of the floor sheets, the diverging portions of each member being connected by a substantially horizontal portion.
104. In a railway car, in combination, a center sill, a pair of downwardly diverging inclined floor sheets disposed on each side of the center sill, and members projecting laterally from each side of the center sill, each of said members being provided with a substantially horizontal portion and inclined portions diverging downwardly from opposite sides of the latter, said inclined and horizontal portions being respectively disposed in supporting cooperation with adjacent portions of said floor sheets.
105. In a railway car, in combination, a center sill involving side walls, and a top wall provided with downwardly diverging portions inclined transversely of the car, each of said side

walls being rigidly provided with a laterally projecting member having downwardly diverging portions inclined longitudinally of the car for supportingly cooperating with inclined floor sheets of the car, each of said longitudinally inclined portions extending downwardly from adjacent the upper edge of the adjacent transversely inclined portion of the top wall.

106. In a railway car, in combination, a center sill having spaced side walls and a top wall, a pair of downwardly diverging inclined floor sheets disposed on each side of the center sill, said side walls being integrally provided with laterally projecting members respectively provided with downwardly diverging portions for supporting adjacent portions of said floor sheets, the upper edges of said diverging portions being connected by a substantially horizontal portion extending transversely of the center sill and constituting a portion of the top wall thereof, portions of the top wall on opposite sides of said horizontal portion being inclined transversely of the car.

107. In a railway car, in combination, a center sill having spaced side walls, a pair of downwardly diverging inclined floor sheets disposed on each side of the center sill, said side walls being respectively provided with laterally projecting members, each of said members being provided with downwardly diverging inclined portions, one of said inclined portions being adapted to support one floor sheet of the adjacent pair and the other of said inclined portions being adapted to support the other floor sheets of said pair.

108. In a railway car, in combination, a center sill, a pair of downwardly diverging inclined floor sheets disposed on each side of the center sill, members rigid with the center sill and projecting laterally therefrom for respectively supporting the inner edges of said floor sheets, and members rigid with the sides of the car and having portions projecting inwardly therefrom for supporting the outer edges of said floor sheets.

109. In a railway car, in combination, a center sill, side sills, a plurality of pairs of downwardly diverging inclined floor sheets disposed on opposite sides of the center sill, members rigid with and projecting laterally from the center sill for supporting portions of the floor sheets adjacent the center sill, and members respectively rigid with the side sills for supporting portions of the floor sheets adjacent the car sides.

110. In a railway car, in combination, a center sill rigidly provided with laterally projecting members, brackets rigid with the car sides, and transversely extending members respectively secured to said brackets and the adjacent laterally projecting members of the center sill, and floor sheets diverging downwardly on opposite sides of each of said transversely extending members, said floor sheets being secured to the latter in overlapping relation.

111. In a railway car, in combination, a center sill having spaced side walls respectively provided with laterally projecting members, side sills, brackets respectively secured to said side sills, transversely extending members respectively disposed on opposite sides of the center sill, each of said transversely extending members being secured to one of said brackets and to the adjacent laterally projecting member of the center sill, and inclined floor sheets diverging downwardly on opposite sides of each of said transversely extending members and rigidly secured thereto in overlapping relation.

112. In a railway car, in combination, a center sill rigidly provided with laterally projecting members, car side stakes, brackets rigidly secured to said side stakes and respectively provided with 5 inwardly projecting portions, transversely extending members respectively disposed on opposite sides of the center sill and respectively secured to said brackets and to the adjacent laterally projecting member of the center sill, and 10 inclined floor sheets diverging downwardly on opposite sides of each of said transversely extending members and rigidly secured thereto in overlapping relation.

113. In a railway car, in combination, a center sill 15 provided with laterally projecting members, brackets rigidly secured to the sides of the car, transverse members respectively disposed on opposite sides of the center sill and respectively secured to said brackets and the adjacent laterally 20 projecting members of the center sill, floor sheets diverging downwardly on opposite sides of each of said transversely extending members and rigidly secured thereto, each of said brackets and said laterally projecting members being provided 25 with inclined portions for supportingly cooperating with adjacent portions of the floor sheets.

114. In a railway car, in combination, a center sill, brackets respectively mounted on the car 30 sides, transversely extending members respectively disposed on opposite sides of the center sill, said members being respectively secured to said brackets and to the center sill, and inclined floor sheets disposed on opposite sides of the 35 center sill, said floor sheets diverging downwardly on opposite sides of said transversely extending members and rigidly secured thereto in overlapping relation.

115. A railway car having a center sill provided with side walls, each of said walls being 40

provided intermediate its upper and lower edges with an outwardly projecting bracket affording means for the attachment of a body bolster, and means extending between said walls rigidly connecting the portions thereof provided with said 5 brackets.

116. A railway car having a center sill provided with side walls, each of said walls being provided adjacent its lower portion with an outwardly projecting bracket affording means for 10 the attachment of a body bolster, and means integrally connecting said walls extending substantially in alignment with the inner ends of said brackets.

117. In a railway car, in combination, a center 15 sill having side walls, each of said side walls being provided adjacent its lower portion with an outwardly projecting bracket, said sill being integrally formed with an upwardly extending bracket having a portion spaced above the top 20 of the sill extending at an angle to the vertical, and a body bolster rigidly secured to each of said brackets and having a portion disposed in overlapping relation with the said portion of the upwardly extending bracket. 25

118. In a railway car, in combination, a center sill having side walls provided with longitudinally extending flanges along their lower edges, brackets respectively formed integrally with the side walls and projecting outwardly from the 30 lower portion thereof beyond said flanges, said sill also having an upwardly projecting bracket provided with a portion spaced above the top of the sill extending at an angle to the vertical, and a body bolster rigidly secured to each of said 35 brackets and having a portion disposed in overlapping relation with the said portion of the upwardly projecting bracket.

WILLIAM E. WINE. 40
